THÉODORE LAFITTE, OF PARIS, FRANCE.

INTERNAL-COMBUSTION ENGINE.

1,186,996.

Specification of Letters Patent. Patented June 13, 1916.

Application filed November 9, 1911. Serial No. 659,319.

To all whom it may concern:

Be it known that I, THÉODORE LAFITTE, citizen of the French Republic, residing at Paris, Department of the Seine, in France, have invented certain new and useful Improvements in Internal-Combustion Engines; and I do hereby declare the following to be a full, clear, and exact description of the invention, such as will enable others skilled in the art to which it appertains to make and use the same.

The present invention has for its object, the provision of an explosion engine with one or more cylinders, its distribution, which is of the four-cycle type, being provided for by means of a single slide valve or sleeve which is preferably, but not necessarily, concentric with the driving piston. This slide valve or sleeve which forms the distributor is connected by a connecting rod with an element to which a combined oscillatory and reciprocatory motion is imparted. Owing to this connection, the slide valve or sleeve effects a reciprocating rectilinear movement or reciprocating rotary movement, so that it is able to produce the phases of the distribution.

The valve sleeve is provided with two orifices serving alternately for the exhaust and admission. This arrangement enables the fresh gases to cool the apertures previously exposed to the burnt gases. Furthermore, the extremity of the sleeve slides on a cylinder end which is fitted internally and forms a hermetic cover. This cylinder end, which may be held by means of a single central nut, permits of a single water outlet and facilitates the construction of a monobloc motor without water piping.

The form of the curve described by the lower extremity of the rod controlling the slide valve varies considerably when the relative values of the elements forming the mechanical connection are modified. If this curve presents the form of a figure 8 with two substantially equal loops, the movement of the valve caused by the rod in describing one of these loops, can be utilized for the admission and the other for the exhaust. The arrangement may also be such that one of the loops of the curve is small enough to permit of the corresponding stroke of the slide valve being inoperative, while the other is sufficiently large to impart to the slide valve, the displacement necessary for the admission and the exhaust.

In the accompanying drawing: Figure 1 is a vertical cross section of the motor; Fig. 2 represents an 8-shaped curve with two equal loops which is described by the lower extremity of the rod; Fig. 3 is illustrative of the case in which the curve described by the lower extremity of the rod presents the form of a figure 8, one of the loops of which is relatively small; Fig. 4 shows the curve comprising only a single loop; Fig. 5 shows another arrangement in which the curve represents a Pascal snail.

The sleeve 2 slides in the cylinder 1 and is provided near its extremity with the admission and exhaust orifices 3 and 4. These orifices are symmetrical and may open respectively into two passages 5 and 6, formed in the guide cylinder 1, opposite two double caps 7 and 8 secured to either side of the motor. These double caps are connected respectively by two collectors 9 and 10, of which 9 communicates with the carburetor and 10 with the exhaust. In the same cap, the conduits serving for the admission and the exhaust are separated by a space 11 in communication with the atmosphere. The admission gases are thus but slightly heated by contact with the burnt gases and enter sufficiently fresh to efficaciously fulfil their purpose of cooling the orifices in the sleeve.

At its upper extremity, the sleeve 2 is guided by the cylinder end 12, which is fitted internally and fixed to the guide cylinder 1 by means of a central nut 13. At its lower part, the sleeve 2 is connected by the pitman 14 with the slide-block 15 at the point 16; the slot or guideway 17, which oscillates around trunnions 18, guides the slide-block 15, which is pivoted at 19, to the crank shaft 20. In these conditions, as the straight line 19-16 always passes through the point 18, and as the distance 19-16 remains constant, it is obvious that the curve described by the point 16 is the conchoid relatively to the point 18, and the circle C described by the point 19, the constant of the conchoid being the distance 19-16. If this distance be designated by m and the distance 18-20 by a , the radius of the circle C by r , then the form of the conchoid A depends upon the relative values of m , a and r . For example, assuming that $a > r$, that is to say, the point 18 is external to the circle C, and $a-r < m < a+r$ an 8-shaped curve is obtained. The arrangement may be such that the two loops of the curve are sub-

stantially equal as shown in Fig. 2. In this case, as the shaft 20 rotates at half the speed of the motor, the operation is as follows: The rotation of the stud 19 produces the reciprocation of the slide-block 15 in the slot 17. The pin 16 of the pitman 14 passes on either side of the trunnions 18, and thus describes the 8-shaped curve represented in Fig. 2. This curve, like the circumference described by 19, is divided into four parts which correspond to the angles adopted for the four-cycle distribution. These angles are indicated at: 21—22 exhaust angle. 22—23 angle between closing 10 the exhaust and opening the admission. 23—24 admission angle. 24—21 compression, explosion and expansion angle. The stud 19 describes these angles in succession in the direction indicated by the arrow and 15 causes the pin 16 of the rod 14 to traverse the parts 21¹—22¹, 22¹—23¹, 23¹—24¹, 24¹—21¹ corresponding to the 8-shaped curve. From 21¹ to 22¹, the pin 16 rises and by the intermediary of the pitman 14, lifts the 20 sleeve 2, causes it to open the orifices 5, and then brings it downward and closes the exhaust. From 22¹ to 23¹, the pin 16 continues its travel, the openings 5 and 6 are closed, the sleeve descends rapidly from 23¹ to 24¹, 25 it opens the admission orifices 6, and the pin 16 containing its travel, lifts the sleeve which closes the admission 6. From 24¹ to 21¹, the pin 16 at first slightly lifts the sleeve, then lowers it, then lifts it again and continuing, reaches at 21¹ the point of opening the exhaust orifices, and the cycle recommences. If the length m be taken sufficiently close to $a+r$, it is possible to obtain a curve A representing a loop of very small 30 size, (Fig. 3). The small loop may be made to correspond to an ineffective displacement of the slide valve, by suitably arranging the orifice 4 of the slide valve 2 and the exhaust and admission orifices 5 and 6. If this condition is fulfilled, the portion p q of the curve A will correspond to the exhaust and the arc s t to the admission. While the point 16 describes the arc t p , the compression phase is produced in the cylinder and 35 then the explosion and the expansion. If the constant m of the conchoid is equal to $a+r$, the curve with a single loop represented in Fig. 4 is obtained; the arcs p q and s t corresponding respectively to the 40 exhaust and the admission.

In the arrangement illustrated in Figs. 2, 3, and 4, the point 16 describes the entire curve A during one revolution of the crank 20. It is for this reason that the shaft 20 is driven 45 off the driving shaft at half speed. When the shaft 18 is located at a distance from the shaft 20 equal to the radius of the crank, a Pascal snail is obtained, the form of which de-

pends upon the value of the constant m . If, for example, m is smaller than the diameter 2¹, the arrangement may be such that the small loop corresponds to an idle travel of the distributing sleeve 2, the orifice 4 not being uncovered. The arc p q (Fig. 5) of the large loop will correspond to the 50 exhaust, the arc s t to the admission. While the point 16 describes the arc t v p , the compression, the explosion, and the expansion will take place. To cause the point 16 to describe the entire curve A, it is necessary that the crank 20 should effect two revolutions. In this manner, a four stroke cycle is obtained by keying the crank shaft 20 directly on the driving shaft. This arrangement presents the advantage of 55 greatly simplifying the mechanism and of rendering the speed reducing gear usually employed for driving the distribution shaft unnecessary.

What I claim is:—

1. In an internal combustion engine provided with suitable ports in the cylinder walls, a valve mounted in said cylinder to coöperate with said ports, a pitman pivoted to said valve, a pivoted guide-way, a block slidably mounted in said guide-way, said pitman being pivoted directly to said block, and means to impart a rotary motion to one end of said sliding block.

2. In an internal combustion engine provided with suitable ports in the cylinder walls, a valve mounted in said cylinder to coöperate with said ports, a pitman pivoted to said valve, a slide to which said pitman is directly pivoted, a pivoted guide-way in which said slide is mounted to reciprocate, and means to impart a rotary motion to one end of said slide to reciprocate the same in the guide and also to oscillate the guide.

3. In an internal combustion engine provided with suitable ports in the cylinder walls, a valve sleeve mounted in said cylinder to coöperate with said ports, a pitman pivoted to said sleeve, a slide to which said pitman is directly pivoted, a guide-way pivoted to a stationary part of the engine and in which said slide is adapted to reciprocate, a rotary member disposed adjacent the slide and to one side of the pivot point of said guide-way, the slide being pivoted directly to said rotary member whereby the slide is reciprocated in the guide-way and the guide-way simultaneously oscillated, for the purpose described.

In testimony whereof I affix my signature, in presence of two witnesses.

THEODORE LAFITTE.
